DESIGN FOR A BOTTLE CARRIER

Albert J. Goodin, Lewiston, Maine

Application January 12, 1944, Serial No. 112,218

Term of patent 14 years

(Cl. D58—4)

To all whom it may concern:

Be it known that I, Albert J. Goodin, a citizen of the United States and a resident of Lewiston, Androscoggin County, Maine, have invented a new, original, and ornamental Design for Bottle Carriers, of which the following is a specification, reference being had to the accompanying drawing, forming part thereof.

Figure 1 is a perspective view of a bottle carrier showing my new design;

Figure 2 is a side elevational view;
Figure 3 is an end elevational view; and
Figure 4 is a perspective view similar to Figure 1 but with the handle in extended position.

I claim:
The ornamental design for a bottle carrier, as shown.

ALBERT J. GOODIN.
